UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

ARTIFICIAL-STONE REFRIGERATOR AND METHOD OF FORMING THE SAME.

Application filed May 21, 1926. Serial No. 110,589.

This invention relates to artificial stone refrigerators and method of forming the same. It has to do particularly with the provision of a method of building and forming the 5 refrigerator structure within a wall whereby the refrigerator unit will be completely enclosed within the walls and the front of the unit will be flush with the wall.

I have found that refrigerators and other 10 similar articles may be formed of artificial stone to present a very compact, light and beautiful refrigerator, or other article, by casting such article of moulded stone formed, preferably, of an oxy-chloride cement. 15 Hitherto these artificial stone refrigerators have been cast or moulded by various different methods, some of which have contemplated casting the refrigerator as a solid unit of stone, and others, the forming of a reinforcing structure, and the moulding or applying of the plastic stone to the interior and exterior of such reinforcing structure or core. The method of applying the plastic stone to the reinforcing core has many advantages 20 over the solid stone refrigerator, but the chief advantage is the fact that such reinforced refrigerators may be subjected to various stresses and strains and sudden jolts without readily cracking or deforming the stone 25 surface of the refrigerator.

The present invention relates to the method of forming a refrigerator unit having parts of its surfaces of artificial stone, but which method of forming is such that the 30 refrigerator may be built with a minimum amount of expense and which may be built on the job and therefore insure a perfect refrigerator ready to use without the necessity of subjecting the same to the jolts and strains 35 incident to shipping.

More specifically, this invention relates to the casting of the refrigerator unit in its place; that is, the reinforcing core and insulating wall of the refrigerator are built 40 complete during the building of the house, apartment, or other structure, and upon the completion, or partial completion of the building, the refrigerator may be completed by the placing of suitable dies or cores in 45 the mould formed by the wall and the artificial stone lining of the refrigerator cast 50 complete.

In the drawings:

Fig. 1 is a perspective view partly cut

away showing the novel refrigerator unit 55 built in the wall of a house or apartment.

Fig. 2 is a sectional side elevation showing the rough refrigerator shell built in the wall and illustrating one method of casting the artificial stone lining on the job.

Although the present method primarily 65 contemplates the forming of a refrigerator unit within a wall, it will be understood that the refrigerator unit or similar article may be formed or cast any place where the reinforcing shell, or mould, may be initially built by the person or contractor building the house or other structure, and so long as the rough 70 reinforcing, or defining structure is initially built and the article to be cast may be simply cast in its place without the use of any other articles with the exception of the casting apparatus.

Any suitable form or shape of mould or reinforcing structure may be utilized in performing my novel method and in the drawings I have illustrated one method of forming a standard refrigerator unit in a wall. In Fig. 1 I have illustrated a refrigerator 75 unit installed complete in a wall. In the performance of this method, as illustrated, the specifications for the rough wooden box, or refrigerating unit are preferably submitted to the person or contractor building the 80 apartment or other structure. This box may be designated 1, and may be very easily and quickly built at the time that the various posts and connecting joists 2 are nailed in place. This box will therefore merely form 85 part of the specifications for the building. Any suitable insulating material or cork board 3 may then be fitted in, or nailed to the rough wooden box 1, and such box is then 90 complete as far as the builder is concerned. This rough wooden box preferably will 95 comprises top, bottom, back and side walls and suitable partitions 4 defining the various chambers of the refrigerator.

At this point, and either before or after the lath and plaster have been applied to the 100 building walls, the dies 5 may be secured in place and the plastic artificial stone poured. This stone preferably consists of an oxy-chloride cement consisting of, for instance, a composition containing dry magnesium powder, and a sand or ground flint aggregation or a combination of both, to 105 which is added enough magnesium chloride

solution to make the mix of the desired consistency to readily pour. This plastic cement may then be poured into the space between the dies 5 and the mould formed by the rough 5 box 1 in any desired manner. That is, the dies may be vibrated, if desired, to secure a suitable setting of the oxy-chloride cement, or the cement pour may be of such fluidity as to settle by gravity. The cement having set 10 to the wooden box, or to the insulated cork lining of such box, the dies may be removed and the complete refrigerator will be built or cast right into the wall. Doors 7, which may be separately cast, or which may be 15 merely wooden doors sprayed with artificial stone, may then be secured to the cast refrigerator to thus form a complete refrigerator unit; no part of which is exposed except the front which will be flush with the wall of the 20 room.

It will be important to note that I have devised a method whereby cast stone refrigerators, or similar articles which have hitherto been only cast by use of expensive moulds 25 and dies, may now be cast in their place of use with a minimum amount of expense and time. By my method the exterior finishing of the refrigerator, or other article, which has heretofore been an expensive and com- 30 plicated undertaking has been entirely done away with, and the box, or reinforcing members are built at the time of building of the house or other structure with very little added expense. As a result of this method 35 an efficient, compact refrigerator is obtained which presents all the desirable features of an ordinary cast stone refrigerator, but which in addition, takes up practically no additional room whatever.

40 What I claim is:

1. The method of casting and installing articles of artificial stone which consists of building up a permanent defining structure of rough boards at the place of use, securing 45 dies in proper position relative to the defining structure whereby said defining structure serves as a mold, then pouring plastic stone in the space between the dies and defining structure and then removing the dies 50 whereby the article is cast in place ready for use.

2. The method of building a refrigerator in a wall which consists in forming a rough 55 refrigerator box as a part of the wall structure, placing a core in the mould formed by the box structure and pouring a plastic cement in the space between the core and mould to form a cast refrigerator unit.

3. The method of building and installing 60 refrigerator units or the like which consists in forming a permanent reinforcing means of rough boards as part of a wall structure, lining the reinforcing means with an insulating shell and then applying plastic

stone directly to the shell to form a refriger- 65 erator unit cast in place.

4. The method of forming cast refrigerator units, or the like, which consists in constructing a shell as part of a wall structure and then cast uniting a covering of stone 70 work to the interior surface of said shell.

5. The method of forming refrigerator units which consists in building up part of the refrigerator structure in place at the place of use to form the rough framework 75 and define the storage compartment or compartments and finishing the remainder by cast uniting a layer of stone work thereto.

6. The method of forming refrigerators as part of a building structure which consists in constructing a part of a wall structure to serve as a rough mold for the refrigerator, lining said wall structure with suitable insulating material, placing a core in the mold formed by the wall structure and the insulating material, pouring a plastic artificial stone in the space between the insulating material and the core and allowing the plastic material to set whereby it will directly adhere to the insulating material after removal of the core.

7. A refrigerator, or cabinet construction, comprising a rough reinforcing and defining structure built up as a part of a building or other place where the refrigerator is to be installed, said reinforcing and defining structure giving shape to the refrigerator and the chamber or chambers thereof, and a shell of cast stone cast united to the interior walls of said rough structure.

8. A refrigerator, or cabinet construction, comprising a shell structure of rough wood boards forming a part of a building structure or other place where the refrigerator is to be used, said rough boards being fitted to give shape to the cabinet or refrigerator, a lining of heat insulating material on some of the inner walls of said shell structure, and a coating of stonework applied in a plastic state directly to the interior surfaces of 105 said insulating material.

9. A built-in refrigerator, or cabinet construction, comprising a rough framework forming a part of the wall of a building structure and extending inwardly from the wall or walls of such building, a lining of heat insulating material on the inner walls of said framework and defining the chamber or 110 chambers of the refrigerator, and a coating of stonework applied in a plastic state to the surfaces of said shell and allowed to set in a solid monolithic coating and extending inwardly from the wall of the building structure.

In testimony whereof I have affixed my 115 signature.

LLOYD G. COPEMAN.
